The ornamental design for a display screen with graphical user interface, as shown and described.

DESCRIPTION

FIG.1 is a front view of a display screen with graphical user interface according to a first embodiment;

FIG. 2 is a front view of a display screen with graphical user interface according to a second embodiment;

FIG. 3 is a front view of a display screen with graphical user interface according to a third embodiment; and,

FIG. 4 is a front view of a display screen with graphical user interface according to a fourth embodiment.

The dot-dash broken lines illustrate an electronic device and form no part of the claimed design. The solid-line rectangle illustrates the perimeter of the display screen of the electronic device. The dashed broken lines illustrate portions of a graphical user interface and form no part of the claimed design.
